UNITED STATES PATENT OFFICE.

JAMES F. BLESS, OF NEWARK, NEW JERSEY.

DESIGN FOR A SAD-IRON.

SPECIFICATION forming part of Design No. 28,866, dated June 14, 1898.

Application filed May 17, 1898. Serial No. 680,991. Term of patent 7 years.

To all whom it may concern:

Be it known that I, JAMES F. BLESS, a citizen of the United States, residing at Newark, in the county of Essex and State of New Jersey, have invented and produced a new and original Design for a Sad-Iron, of which the following is a specification, reference being had to the accompanying drawings, forming part thereof, in which—

10 Figure 1 is a perspective view of a sad-iron bearing and incorporating my design. Fig. 2 is a central vertical longitudinal section of same, the dotted line 3 3 denoting the section on which Fig. 3 is taken; and Fig. 3 is a 15 central vertical transverse section of same, the dotted line 2 2 denoting the section on which Fig. 2 is taken.

The leading feature of my design consists of the new and original shape and configuration of the sad-iron, as shown in the drawings.

In the drawings, A designates the sad-iron, which is of elongated form and has at oppo-

site sides of its upper surface the raised sections B B, which, as shown, correspond with one another and have flat top surfaces whose 25 outer edges are sharply defined by the sides of the iron and whose inner edges are likewise defined by the inner vertical walls C of said sections B B.

Centrally between the raised sections B B, 30 but on a lower plane, the iron has an elongated cavity D, traversed by the bar E, as shown.

What I claim is—

The design for a sad-iron; substantially as 35 shown and described.

Signed at Newark, in the county of Essex and State of New Jersey, this 10th day of May, A. D. 1898.

JAMES F. BLESS.
